UNITED STATES PATENT OFFICE.

JEAN BAPTISTE GUSTAVE ADOLPHE CANET, OF PARIS, FRANCE, ASSIGNOR
OF ONE-HALF TO SIR JOSEPH WHITWORTH & COMPANY, (LIMITED,) OF
OPENSHAW, ENGLAND.

APPARATUS FOR CHECKING OR CONTROLLING THE RECOIL OF GUNS.

SPECIFICATION forming part of Letters Patent No. 430,920, dated June 24, 1890.

Application filed January 23, 1889. Serial No. 297,276. (No model.) Patented in England January 4, 1888, No. 146, and in France March 5, 1888, No. 184,711.

To all whom it may concern:

Be it known that I, JEAN BAPTISTE GUSTAVE ADOLPHE CANET, engineer, a citizen of the Republic of France, and a resident of 5 Paris, France, have invented new and useful Improvements in Apparatus for Checking or Controlling the Recoil of Guns and for Effecting the Return of the Same to the Firing Position, (for which I have obtained a patent 10 in the following countries: in Great Britain, No. 146, dated January 4, 1888, and in France, certificate of addition, No. 184,711, dated March 5, 1888,) of which the following is a 15 specification, reference being had to the accompanying drawings.

This invention relates to improvements in apparatus for checking or controlling the recoil of a gun and for storing up energy during such recoil, to be utilized for running out 20 or returning the gun to its firing position.

My improvements are very advantageously applicable to gun-mountings of the kind or class wherein the gun is supported by a cradle or top carriage arranged to slide upon a 25 chassis or frame under the control of hydraulic brakes, and having combined therewith springs which are compressed during the recoil, and which by their reaction effect the running out or return of the gun to the 30 firing position. The said improvements are, however, also applicable to other gun-mountings wherein the running out of the gun after its recoil is effected by the stored-up energy of springs acting as recuperators.

35 In such gun-mountings as heretofore constructed the recuperator-springs must be of great length, in order that the gun may recoil through a distance sufficient to allow its motion to be gradually arrested or checked 40 by the brakes. In some instances the said springs are of such length that they project to an inconvenient and objectionable extent beyond the chassis or frame of the gun-mounting.

45 The main object of the present invention is to provide for diminishing the length of the space required for the recuperator-springs without diminishing the distance through

which the gun can move in its recoil. For this purpose I substitute for a spring which 50 exerts the whole of its elastic resistance in a single straight line one which exerts such resistance with the same effect in two or more parallel lines; or, in other words, I divide the length of a spring into two or more portions 55 or sections and arrange the same parallel and in such relation to each other that they exert the same force as but occupy a shorter space than the undivided spring—that is to say, I do not propose by my said invention to diminish the length or extent of a spring in the 60 sense of diminishing the number or length of the elastic portions or elements of which the spring is composed; but instead of arranging these elastic portions or elements in one continuous straight line I place them in two or more parallel lines without changing their relation to each other in respect to their combined action or effect, and in carrying my invention into practice I arrange the separate 65 springs or sections of a spring in such a manner that one forms the bearing or abutment for another, so that the force of the recoil will be transmitted from one to the other.

In the accompanying drawings I have 70 shown one form of gun-mounting having applied thereto apparatus constructed according to my invention and comprising three springs, or a spring divided into two sections, one consisting of a single spring and the 75 other of two springs, all arranged parallel to each other.

Figure 1 is a side elevation, partly in vertical longitudinal central section, and Fig. 2 a plan, partly in horizontal section, on the 80 line x x , Fig. 1, the parts being shown in the firing position. Fig. 3 is also a plan, partly in horizontal section, on the line x x , Fig. 1, the parts being shown in the recoiled position; and Fig. 4 is a rear elevation, partly in transverse section, on the lines x' x' and x^2 x^2 , Fig. 1.

Like letters indicate corresponding parts throughout the drawings.

A is the base-plate or racer; B, the chassis, 90 frame, or under carriage; C, the cradle or top

carriage, in which the gun D is supported by its trunnions D', suitable hydraulic brakes being provided for counteracting or resisting the recoil.

5   *a a* are rods having heads *a'* and secured in lugs or brackets B', formed on the sides, transoms, or cheeks of the chassis or frame B. Each of these rods *a* is combined with a spring *b*, which preferably surrounds the rod, 10 and at its rear end bears or abuts against a ring or collar *a²*, held upon the said rod by a nut *a³*, whereby the initial compression of the spring *b* may be regulated as desired.

15   *c* is a cross-head or cross-bar, which is fitted to slide upon the rods *a*.

20   *d* is a rod, which from its head *d'* extends through the center of the cross-head *c* and through a sleeve or cylinder *e*, formed with or firmly attached to the cradle or top carriage C. The rod *d* is combined with a spring *f*, which surrounds the said rod and bears or abuts at its rear end upon an adjustable cap or disk *g*, which is secured on the rod by locking-nuts *d²* *d³*, or by other convenient 25 means, the said spring *f* being inclosed and protected by the said sleeve or cylinder *e*, as shown.

30   I prefer that the springs above mentioned should be formed of the well-known "Belle-ville" disks or washers; but spiral or other springs will serve my purpose. The two springs *b* form virtually one section and the spring *f* the other section of the recuperator—that is to say, the two springs *b* combined, as shown, with the spring *f*, produce 35 in the recuperator the same effect of force or resistance as would be produced by the addition to the spring *f* of a number of disks or washers equal in elastic force to the two springs *b*, arranged parallel to each other, and it is desirable that the strength or resistance of each of the springs *b* should be about one-half of that of the spring *f*, and that the 40 length of each spring *b* should be about double that of the spring *f*, or the number of disks of each spring *b* should be about double the number of those of the spring *f*.

45   When the gun is fired, the top carriage C recoils therewith under the control of its brakes upon the chassis or frame B, carrying 50 with it the said sleeve or cylinder *e*, and thus compressing the central spring *f*. At the same time the force of the recoil, being transmitted through this spring and through the 55 cap or disk *g* to the central rod *d*, causes this rod by its head *d'* to pull the cross-head *c* backward, thereby compressing the springs *b* upon the side rods *a*, the heads *a'* of which, bearing against the brackets B', hold the said 60 rods so that their collars *a²* support the ends of the said springs during the compression of the latter, the position of the parts at the 65 termination of the recoil being shown in Fig. 3. The recuperator-springs *b f* act in combination with the hydraulic brakes in checking or controlling the recoil of the gun. When the recoil ceases, the said springs *b f*, unless

restrained, will react and run out the gun and top carriage to the firing position. If desired, however, suitable devices may be 70 provided for retaining the gun in its recoiled position for any required length of time and for then releasing it by hand.

75   The forward ends of the springs *b* form bearings, abutments, or points of support for the cross-head *c*, and consequently for the spring *f*, which bearings or abutments themselves move, and thus permit the backward movement of the sleeve *e* with the gun and top carriage in the recoil.

80   The movement of the sleeve or cylinder *e* relatively to the cap or disk *g* and the movement of the cross-head *c* relatively to the bearings or abutments *a²* will together be equal in length to the recoil movement of the 85 gun. Therefore, although the entire recuperator apparatus is so arranged that it does not project beyond the chassis or frame, it allows the gun to recoil through the desired distance.

85   In the gun-mounting shown in the drawings I use for retaining the gun in its recoiled position a spring bolt or catch *h*, adapted to enter one or the other of the notches *C' C²* in the under side of the top carriage, 90 according to the distance through which the gun and top carriage recoil. The bolt or catch *h* is coupled to a lever *j*, which is pivoted at *j'* to the chassis or frame B, and whereby the said bolt or catch may be withdrawn from the notch to permit the running out of the gun.

95   Suitable means are provided for diminishing the concussion at the termination of the running-out or return movement of the gun. 100 In the drawings I have shown buffers or cushions for this purpose formed of Belleville disks or springs *k* and placed upon the rods *a* between the cross-head *c* and the lugs or brackets B'.
110

115   It is obvious that the arrangement of the recuperator-springs relatively to each other can be somewhat modified while retaining the principle of my invention; also, that the top carriage may, if desired, be otherwise connected with the spring through which the force of the recoil is to be first transmitted. It is, moreover, evident that my invention is applicable to gun-mountings in which recoil-brakes are used in combination with recuperators having a piston arranged to work in a cylinder and to be acted upon by fluid-pressure generated by the recoil, so as to store up energy in springs and subsequently utilize such energy for running out the gun.
120

125   By increasing the number of springs or sections and movable bearings, abutments, or points of support of the recuperator apparatus I can reduce to a corresponding degree the length of the space occupied by the said apparatus without diminishing its efficiency.
130

Having now particularly described and ascertained the nature of my said invention and in what manner the same is to be per-

formed, I wish it understood that this invention does not comprise a series or group of springs which exert their force or resistance independently of each other, as in the case of 5 two or more spiral or other springs arranged side by side, each supported by a fixed bearing or abutment, whereas in my springs the parallel arrangement of the parts or sections is in all cases combined with the continuity 10 of the elastic or resilient action from one to the other end of the series of disks, coils, or other elements of the spring; and

I claim—

1. In a gun-mounting, the combination, 15 with the recoiling and non-recoiling parts of the said mounting, of a recuperator-spring divided into sections, one of which bears at its forward end against a shoulder or projection on the recoiling part and another of which 20 bears at its rear end against an abutment on the non-recoiling part, and a movable bearing or abutment which is connected with the rear end of the first section and bears against the forward end of the second section, so that 25 it will transmit the force of the recoil from one section to another, for the purposes above specified.

2. In a gun-mounting, the combination, 30 with the recoiling and non-recoiling parts of the said mounting, of a recuperator-spring composed of sections arranged parallel to each other, one of which bears at its forward end against a shoulder or projection on the recoiling part and another of which bears at 35 its rear end against an abutment on the non-recoiling part, and a movable bearing or abutment which is connected by a rod or bolt with the rear end of the first section and bears against the forward end of the second section and which transmits the force of the recoil from one section to another, for the purposes above specified.

3. In a gun-mounting, the combination, 45 with the recoiling and non-recoiling parts of the said mounting, of a recuperator-spring composed of sections arranged parallel to each other, one of which bears at its forward end against a shoulder or projection on the recoiling part and another of which bears at 50 its rear end against an abutment on the non-recoiling part, a movable bearing or abutment which bears against the forward end of the second section and is connected by a rod or bolt with the rear end of the first section 55 and which transmits the force of the recoil from one section to another, and a spring or buffer arranged between the said movable abutment and a shoulder or projection in front thereof on the said non-recoiling part, 60 for the purposes above specified.

4. In a gun-mounting, the combination, 65 with the recoiling and non-recoiling parts of the said mounting, of a recuperator comprising pairs of concavo-convex plates or disks arranged in series or groups which are parallel to each other, and one of which bears at

its forward end against a shoulder or projection on the recoiling part and another at its rear end against an abutment on the non-recoiling part, and a movable bearing or abutment which bears against the forward end of the second series or group and is connected by a rod or bolt with a plate or disk bearing against the rear end of the first series or group, so that the said series or groups will 75 be simultaneously compressed by the recoil and will by their reaction effect the running out of the gun.

5. In a gun-mounting, the combination, 80 with the chassis or under carriage and the cradle or top carriage, of a rod secured in the said under carriage and provided with a bearing or abutment, a spring mounted upon the said rod, a movable bearing or abutment arranged to slide upon the said rod, a rod secured at one end in the said movable bearing or abutment and provided at its other end with another bearing or abutment, a spring mounted upon this rod, and a bearing or abutment on the cradle or top carriage arranged to act upon the said spring in the recoil, substantially as and for the purpose set forth.

6. In a gun-mounting, the combination, 85 with the cradle or top carriage and the under carriage, of a central and two side springs arranged parallel to each other, a cylinder or sleeve formed or fixed on the top carriage and inclosing the said central spring, a rod extending through the said spring and provided with an abutment therefor, a cross-head which is carried by the said rod and which extends to and acts upon the side springs, and rods which extend through the 90 said side springs and are provided with abutments therefor and which are connected with the under carriage, substantially as and for the purpose specified.

7. In a gun-mounting, the combination, 95 with the under carriage B and the cradle or top carriage C, of the sleeve or cylinder e, formed or fixed on the said top carriage, a spring f inclosed in the said sleeve or cylinder, a rod d, extending through the said spring and provided with a bearing or abutment g 100 therefor, a cross-head or movable bearing or abutment c, carried by the said rod, side rods a, which are secured to the said under carriage and are provided at their rear ends with bearings or abutments a² and upon which the 105 said cross-head c is arranged to slide, and springs b, arranged upon the said side rods between the abutments a² and cross-head c, substantially as and for the purposes set forth.

8. In a gun-mounting, the combination, 110 with the under carriage B and the cradle or top carriage C, of the sleeve or cylinder e, formed or fixed on the said top carriage, a spring f inclosed in the said sleeve or cylinder, a rod d, extending through the said spring 115 and provided with a bearing or abutment g therefor, a cross-head or movable bearing or

abutment *c*, carried by the said rod, side rods *a*, which are secured to the said under carriage and are provided at their rear ends with bearings or abutments *a*² and upon which the said cross-head *c* is arranged to slide, springs *b*, arranged upon the said side rods between the abutments *a*² and cross-head *c*, and springs or buffers *k*, also arranged upon the said side rods between the cross-head *c* and projec-

tions *B'* on the under carriage, substantially 10 as and for the purposes set forth.

In testimony whereof I have hereunto signed my name in the presence of two subscribing witnesses.

JEAN BAPTISTE GUSTAVE ADOLPHE CANET.
